(57) **CLAIM**

The ornamental design for a fluid coupling, as shown and described.

DESCRIPTION

FIG. 1 is a perspective view of a fluid coupling showing our new design.

FIG. 2 is a first end view of the fluid coupling.

FIG. 3 is a second end view of the fluid coupling.

FIG. 4 is a first side view of the fluid coupling.

FIG. 5 is a second side view of the fluid coupling.

FIG. 6 is a top view of the fluid coupling; and,

FIG. 7 is a bottom view of the fluid coupling.

The broken lines represent portions of the fluid coupling that form no part of the claimed design. The dash dot broken lines define the boundaries of the claim and form no part thereof.
